UNITED STATES PATENT OFFICE

HENRY KINNEY, OF SACRAMENTO, CALIFORNIA

TRANSPOSING KEYBOARD

Application filed March 8, 1927. Serial No. 173,706.

This invention resides in a mechanical means for transposing music and deals particularly with pianos, organs, accordions and like instruments.

5 One object is to provide a means whereby the instrument may be made to produce music in any key regardless of the key in which the composition is written.

This may be accomplished in one of two 10 ways. First, the tone producing portion of the instrument may be shifted laterally of the keyboard, or the keyboard itself may be shifted. The latter method is used for illustration and description in this case, since it 15 lends itself more easily to manipulation in most instruments.

Now suppose all compositions were written in the key of C. This, incidentally, would facilitate composition, but further it would 20 aid the player, in that he would have no black digits to manipulate, excepting, of course, accidentals. And with my shifting keyboard he could play in any key, from the same composition, and still avoid the black digits no 25 matter how many tones up or down the scale he shifted the keyboard to accommodate the desired key. As a matter of fact, he could play in twelve keys from one composition and not use one black digital, except for accidentals. From the above it is obvious that 30 if all compositions were written in C and had no accidentals introduced, the black digits could be discarded and removed entirely. This produces a new situation in music where 35 the only use for black digits is to introduce a foreign note or secondary tone instead of the primary tones of a different key.

It is also to be understood that any composition whatsoever, written in any key, may by 40 means of this shifting keyboard be fingered as written, but played in any one of the twelve keys desired.

One advantage of this arrangement results 45 in accommodating the piano or like instrument to the pitch of the voice or instrument that is to be accompanied. Instead of forcing the voice up or down to reach the key in which the piece is written, the keyboard is shifted up or down and the piece played as 50 written.

Music is not usually written in G-flat or B-natural because the key is too difficult, since it introduces a large number of black digits, and yet there is no reason why it should not be used as much as C major or A minor. With 55 my device, the composition could be written in C, and then the keyboard shifted to G-flat or B. The piece could be played as if in the key of C, although in reality the playing would be in G-flat or B-natural with all the 60 harmonies of these particular keys realized without any of their difficulties. With my shifting keyboard, the entire scale is available for such purposes.

The foregoing discussion deals with the 65 theory of the transposing keyboard, while the accompanying drawings show one embodiment of my idea, with two modifications. For a more detailed description, I refer now to the drawings, in which: 70

Figure 1 shows cross section of a modern piano keyboard, modified to allow keyboard to shift;

Figure 2 shows fragmentary front elevation of same piano partly in section; 75

Figure 3 shows modified form of keyboard to accommodate a mode of fifty-three intervals;

Figure 4 shows diagrammatical view of a keyboard with key indicator; 80

Figure 5 shows same view in shifted position;

Figure 6 shows arrangement when applied to reed organ;

Figure 7 shows fragmentary plan view of 85 accordion keyboard partly in section; and

Figure 8 shows a cross section of same.

In Figure 1, the white digits of an ordinary piano keyboard are generally designated by the numeral 1, which digits rest 90 on felt strips 2 that are carried on a supporting beam 3. Small pins 4, driven into the beam 3, serve as guides to align the digits and hold them in striking position under the upright rods 5, which rods are a part of the 95 tone-producing mechanism. A strip 6 runs along the inner ends of the digits and is equipped with pads 6 to deaden the noise, while the outer ends are suitably equipped to fit over guide pins 7 and strike against 100

small pads 8 around the base of pins 7. The black digitals 9 have the same construction, but use guide pins 10 and striking pads 11. The above described mechanism provides the generally accepted standard keyboard construction.

Beneath the outer ends of the keys, and carrying pins 7 and 10, there is provided a strip 12. Near each end of said strip there is a pin 13 designed to fit into holes 14 provided in a lower strip portion 15, said strip portion 15 being attached by screws 16 to a stationary member 17. Said member 17 is provided with a plurality of apertures 18 designed to permit a sufficient number of suitable rollers generally designated 19 to be inserted and attached to the lower member 20, as at 21. The upper surfaces of these rollers bear against a strip 22, which strip 22 parallels and is directly beneath the previously mentioned strip 3 to which it is attached by screws 23.

A sheet 24 of acceptable material is suitably attached to strips 3, 6 and 12. This sheet 25 serves a twofold purpose; one is to hold the keyboard isolated from the rest of the construction; the other is to give rigidity to the movable portion of the keyboard structure so that it may be shifted and not have a tendency to distort.

At each end of the keyboard there is provided a piece of suitable material designated 26 which carries the ends of strips 3, 6 and 12, also the end of the front board 27, which board is held rigid by the brackets 28 and 29. Handles 30 are mounted on said board 27 and are used to grasp the keyboard for shifting.

The front of the movable portion of the keyboard is equipped with a nomenclature plate 31. A similar plate 32 is attached to the fixed part of the keyboard structure. These plates, used in conjunction, provide the means for determining the key or keys in which the composition is to be played, and are used as follows:

Suppose the composition to be played was written in C major, and it was desired to play it in D major.

By referring to Figures 4 and 5, where a diagrammatic arrangement is shown, it is clearly seen that the key of C major, Figure 4, becomes the key of D major, Figure 5, by shifting the keyboard laterally. The top lettered portion 35 represents the rods 5 of the other views, while the digitals remain the same.

In Figure 2 the keyboard is arranged so that the key of C is transposed to F; D to G; E to A; etc.

Figure 3 represents a method whereby the ordinary octave is adapted to the mode of 53 intervals. The same plan of shifting would be used as in the other case.

Figure 6 shows a plan view of an arrange-

ment of my invention applied to an organ. The keyboard is constructed to slide laterally. By grasping the handles 40 and raising the keys until they clear the pins 41, the board may then be moved to any lateral position desired. A pin 42 is provided which extends into holes 43 to align the keys over the pins 41 in any position.

Figure 7 displays a fragmentary top plan view of an accordion with my shifting attachment, while Figure 8 shows a cross section of the instrument.

In this case the entire keyboard is mounted on a member 45 which member is provided with a screw threaded bolt 46 adapted to extend through a slot 47 cut in the outer casing, and to receive a thumb nut 48.

End pieces 49 carry the pivot rod for the white digitals 50, and also the black digitals 51.

Since there is only a pressure contact between the toe 52 of the key and the end 53 of the valve generally designated 54, it is plainly evident that after loosening the thumb nut 48 the keyboard may be shifted laterally of the valves. Nomenclature plates 55 and 56 are provided to determine the keys desired.

Figure 3 shows diagrammatically how each octave may be divided into 53 equal tones and how the twelve keys are connected to twelve of these tones, when playing in one key, and connected to another twelve when playing in another.

The foregoing description and specification pertain to only a few of a wide variety of applications which it is possible to make but impossible to show. Therefore I reserve the right to make all modifications and refinements that do not depart from the spirit of the description, nor the scope of the appended claim.

I claim:

A transposing keyboard comprising a string-supporting frame, means carried by said frame for vibrating said strings, a movable keyboard carried by said frame and being adjustable with respect to said string-vibrating means, said keyboard being manually movable, means for securing said keyboard in adjusted position, a rail secured to the underside of said keyboard, flanged rollers carried by said frame for supporting said rail, a second rail disposed near the front of said keyboard and being secured to said frame, the front of said keyboard resting upon said second named rail.

HENRY KINNEY.
